UNITED STATES PATENT OFFICE.

HENRY H. LADD, OF HARVARD, ILLINOIS.

DESIGN FOR A CHIMNEY-HOLE CAP.

SPECIFICATION forming part of Design No. 30,905, dated May 30, 1899.

Application filed December 6, 1897. Serial No. 661,006. Term of patent 7 years.

To all whom it may concern:

Be it known that I, HENRY H. LADD, a citizen of the United States, residing at Harvard, in the county of McHenry and State of Illinois, have invented and produced a new and original Design for Chimney-Hole Caps; and I do hereby declare the following to be a full, clear, and exact description of the invention, such as will enable others skilled in the art 5 to which it appertains to make and use the same, reference being had to the accompanying drawings, forming a part of this specification.

The accompanying drawing illustrates my 15 design for a chimney-hole cap in perspective.

As shown in the drawing, the leading feature of my design consists in a concavo-con-

vex cap A, as of sheet metal, having a central hole or opening B and a peripheral flange C, provided with radial grooves or corrugations D, which are formed in and made a part of the sheet metal of which the cap A is composed in the act of stamping the whole.

Having thus described my design, what I claim as new, and desire to secure by Letters 25 Patent, is—

The design for a chimney-hole cap substantially as herein shown and described.

In testimony whereof I affix my signature in presence of two witnesses.

HENRY H. LADD.

Witnesses:

S. RICHARDSON,
FRANK WHAPLES.
